UNITED STATES PATENT OFFICE

112,120

DESIGN FOR A ROWBOAT

Charles G. MacGregor, Lynn, Mass.

Application June 11, 1938, Serial No. 77,765

Term of patent 14 years

To all whom it may concern:

Be it known that I, Charles G. MacGregor, a citizen of the United States and a resident of Lynn, county of Essex, State of Massachusetts, have invented a new, original, and ornamental Design for a Row Boat, of which the following is a specification, reference being made to the accompanying drawing, forming part thereof.

In the drawing:

Fig. 1 is a top plan view of a row boat showing my new design;

Fig. 2 is a side elevational view;

Fig. 3 is a stern view in elevation; and

Fig. 4 is a bow view in elevation.

I claim:

The ornamental design for a row boat, as shown.

CHARLES G. MACGREGOR.
